UNITED STATES PATENT OFFICE.

BERNARD DOUGLAS, OF NEW YORK, N. Y.

IMPROVED BOOT-JACK AND BLACKING-CASE.

Specification forming part of Letters Patent No. **58,230**, dated September 25, 1866.

To all whom it may concern:

Be it known that I, BERNARD DOUGLAS, of the city, county, and State of New York, have invented a new and Improved Boot-Jack and Blacking-Case Combined; and I do hereby declare that the following is a full, clear, and exact description thereof, which will enable others skilled in the art to make and use the same, reference being had to the accompanying drawings, forming part of this specification, in which—

Figure 1 represents a plan or top view of the apparatus when opened so as to form the boot-jack. Fig. 2 is a bottom view of the same. Fig. 3 is a longitudinal vertical section of the same, the apparatus being represented as folded up.

This invention relates to a very simple apparatus, which will especially recommend itself to travelers, as it confines within a very small area a blacking box and brush, and when opened receives the shape and properties of a boot-jack of the common style.

The invention consists in so constructing a wooden box that the same is made of two parts, which when closed keep the blacking-brush and the blacking well inclosed; but as soon as opened the box will assume the shape of a boot-jack, and effectively perform the services of such an instrument.

A represents a box or case, which is cut into two parts, connected by hinges *a*.

The blacking-box *b* is inserted in a hole cut into one of the covers, and rests on a metal strip, *c*, and is closed by a cover, *d*, which swings on the pin *e*, and can be opened by turning it on the same.

The blacking-brush *B* is held between two guide-blocks, *f*, which fit into two small re-

cesses cut into the sides of the brush, as seen in Fig. 2.

The necessary heel-shaped recess is cut into the cover of one of the halves of the case, to conform the same to the shape of a boot-jack when the case is opened, as seen in Figs. 1 and 2 and in red lines in Fig. 3.

The two parts of the case are so arranged that one is considerably higher than the other, so that the front of the boot-jack will be higher than its rear end, as is usually the case. For this purpose the hinges are not applied to the center of the case, but somewhat below the same, and the line of division between the two parts slants down, so as to make the rear end, *g*, of the boot-jack considerably lower than its front end, *h*.

This device will prove itself to be very handy for travelers, as it is very compact in construction, and does not occupy much room in a trunk or valise, besides keeping the unclean blacking-brush incased in a neat and clean box.

Having thus described my invention, I claim as new and desire to secure by Letters Patent—

A combined boot-jack and blacking-case, constructed by combining the two unequal parts of the case *A* with the hinges *a*, blocks *f*, and cover *d*, substantially in the manner and for the purpose herein shown and described.

The above specification of my invention signed by me this 2d day of August, 1866.

BERNARD DOUGLAS.
